The ornamental design for a clutch cover especially for automotive racing applications, as shown and described.

DESCRIPTION

FIG. 1 is a left side elevational view illustrating a clutch cover, especially for automotive racing applications in accordance with my new design;

FIG. 2 is a cross-sectional view of the clutch cover especially for automotive racing applications of my new design illustrated in FIG. 1 as taken along section line 2—2 of FIG. 3; and,

FIG. 3 is a rear elevational view of the clutch cover especially for automotive racing applications of my new design illustrated in FIGS. 1 and 2.

The side elevational view of FIG. 1 is substantially continuous about the periphery of the clutch cover especially for automotive racing applications of my new design. The front elevational view of the clutch cover does not form part of the claimed invention.
